UNITED STATES PATENT OFFICE.

HARRY H. DODGE, OF BUFFALO, NEW YORK.

CONTROL VALVE FOR GASEOUS-FUEL BURNERS.

Application filed August 2, 1923. Serial No. 655,377.

To all whom it may concern:

Be it known that I, HARRY H. DODGE, a citizen of the United States, and a resident of Buffalo, in the county of Erie and State 5 of New York, have invented certain new and useful Improvements in Control Valves for Gaseous-Fuel Burners, of which the following is a full, clear, and exact description.

The invention appertains to gaseous fuel 10 burners and in particular to valves for controlling the supply of fuel to such burners.

The primary object of the invention is the provision of a unitary valve for use with burners employing a plurality of gaseous 15 fuel elements, so constructed that a constant proportional flow of fuel is maintained therethrough during manipulation of the valve and in all open positions thereof.

Other objects are: the provision of a fuel 20 proportionating control valve for gaseous fuel burners; the provision in such a valve of means for permitting passage therethrough at a plurality of points of a constant predetermined volume of fuel; the provision in such a valve of means for preventing admixture of fuel in the valve; the provision in such a valve, of means for adjustable regulation thereof without altering a predetermined proportional passage of fuel therethrough; and such other objects as will be 25 hereinafter apparent from the description to those skilled in the art.

The invention resides in the details of construction, combination and arrangement 30 of parts, as will be hereinafter more fully described, set forth in the appended claims, and illustrated in the accompanying drawings, in which:—

Figure 1 is a longitudinal cross section 35 through a valve constructed in accordance with the invention,

Figure 2 is a section on line 2—2 of Figure 1, and,

Figure 3 is a section on line 3—3 of Figure 1.

In this preferred embodiment of the invention, the valve is designed and adapted 40 for use in connection with burners utilizing natural gas and air as its fuel. For a proper combustion of this mixture, a proportion 45 of one cubic foot of gas to ten cubic feet of air is required, as the general rule. In Figure 1, the invention is illustrated in detail, and comprises a brass or other metal casting 1 having a central longitudinal bore therethrough, reamed to receive a valve

stem 2 therein. At each end of the casting, the stem 2 projects therebeyond, terminating in externally threaded portions 3 slidable through packing sleeves 4 inserted at 60 each end of the casting. Threaded over the portions 3 of the valve stem 2, at each end, are valve operating and adjusting members consisting of hand wheels 5, which bear against the ends of the packing sleeves 4, so 65 that on rotation of a wheel, by reason of its engagement with the valve stem end, the stem will be caused to move longitudinally within the casting. To insure this movement of the valve stem, the casting is provided with a key 6 passed through a wall 70 thereof and engaged in a longitudinal groove or keyway 7, formed in the body of the stem, whereby rotation of the valve stem is prevented, while allowing free longitudinal 75 rotation thereof.

At suitably spaced points, the body of the casting 1 is provided with diametrically aligned lateral passages or bores 8 and 9, 80 communicating with the bore of the casting, and extending through connecting nipples 10 and 11 respectively, formed on the outer face of the casting. One nipple 10 is adapted for connection with the air intake A of the burner B, while the other nipple 11 85 is similarly adapted for connection with the gas intake conduit G of the burner. Similar nipples 12 and 13 respectively are formed on the opposite side of the casting for connection with air and gas conduits (not 90 shown).

The valve stem 2 is provided at points corresponding to the distance between the casting bores 8 and 9, with transverse passages 14 and 15 corresponding in width to 95 the width of the said casting bores. These passages 14 and 15 are adapted to register with the casting bores 8 and 9 on proper movement of the valve stem 2, and the volume of flow therethrough is regulated by 100 adjusting the stem to restrict or open the passages as is obvious. The bore 8 and the passage 14 are adapted for the passage of air therethrough, and, as has hereinbefore been stated, by reason of the proportion ten 105 cubic feet of air to one foot of gas necessary, the air passageway is ten times the cross-sectional area of the gas passageway, consisting of the bore 9 and the passage 15. Mixture of the air and gas within the casting 1 is prevented by the packing of grease, 110 fed from a cup 16 on the casting and com-

municating with a milled slot 17 in the casting and surrounding the valve stem.

In operation, the operating wheels 5 are turned to move the valve stem longitudinally within the casting 1 to bring more or less of the transverse passages in the stem 2 into registry with the bores of the casting, permitting a regulation of the fuel flow therethrough. By reason of the predetermined proportional arrangement of the passageways, the flow of air and gas will at all times have a constant proportion, irrespective of the regulation of the burner flame by the valve. If desired, the valve wheels may be removed, when the burner is properly adjusted, or locknuts or the like (not shown) applied to the ends of the stem, for maintaining adjustment.

While a preferred embodiment of the control valve has been described and illustrated herein in specific terms and details of construction and arrangement, it is to be understood that various changes in and modifications of the same may be resorted to without departing from the spirit of the invention, or the scope of the claims appended hereto. Also it will be understood that though the invention has been described as using natural gas and air, other forms of gases may be employed, the valve being adjustable for all conditions of supply.

Having thus fully described the invention, what is claimed, is:—

1. A valve for mixed gaseous fuel burners comprising a valve body provided with fuel passages, a valve stem longitudinally movable in said body to open and close said valve, means for operating said stem, and means in said stem for proportionating flow of fuel through the valve in all open positions thereof.
2. A valve for mixed gaseous fuel burners comprising a valve body provided with fuel passages, a valve stem longitudinally movable in said body to open and close said valve, fuel passages in said stem and of relatively proportional dimensions, and means for operating said stem for simultaneous registering of all of said passages.
3. A valve for mixed gaseous fuel burners comprising a valve body provided with separate spaced fuel passages, a valve stem

longitudinally movable in said body to open and close said valve, separate spaced fuel passages in said stem and of different dimensions, said passages being proportionate in dimensions to the requisite proportion of fuel mixture, and means for operating said stem for simultaneous registry of said passages.

4. A valve for mixed gaseous fuel burners comprising a valve body provided with separate fuel passages for each fuel, a valve stem longitudinally movable in said body to open and close said valve and provided with longitudinally spaced passages for registry with said body passages, said passages being of different and relatively proportional cross sectional area to correspond with the proportionate mixture of fuel, and means for operating said stem for simultaneous registry of said passages.

5. A valve comprising a body having a series of spaced ports, a stem longitudinally movable therein to open and close said valve and having longitudinally spaced passages of different and relatively proportional dimensions, and means for moving said stem for simultaneous and adjustable registry of each of said stem passages with certain of said valve ports.

6. A valve comprising a tubular body having a series of oppositely aligned spaced ports, a stem longitudinally movable in said body to open and close said valve, means for operating said stem, and means in said stem for permitting a predetermined and constant proportional flow of fuel through said ports in all open positions of said valve.

7. A proportional valve for mixed gaseous fuel burners comprising a tubular body casting provided with longitudinally spaced oppositely aligned ports, a valve stem disposed in said casting against rotation, means for moving said stem longitudinally in the casting to open and close said valve, and fuel passages being provided in said stem in a longitudinally spaced relation to correspond with the spacing of said ports, said passages being of different dimensions with the cross sectional area thereof proportionate to the volume of fuel to be passed through each for the fuel mixture.

HARRY H. DODGE.
